Des. 228,075
Patented Aug. 7, 1973

228,075

ANIMAL FIGURE PUNCH-OUT BOARD OR SIMILAR ARTICLE

Harry Zelenko, 150 E. 61st St.,
New York, N.Y. 10021

Term of patent 3½ years

Filed May 6, 1971, Ser. No. 141,097

Int. Cl. D21—01
U.S. Cl. D34—2 R

Fig. 1

Fig. 2

FIG. 1 is a top plan view of an animal figure punch-out board, showing my new design; and

FIG. 2 is a side elevational view thereof, on a reduced scale.

I claim:

The ornamental design for an animal figure punch-out board or similar article, substantially as shown.
